UNITED STATES PATENT OFFICE.

WILLIAM E. LAWRENCE, OF NEW YORK, N. Y.

CURRY-COMB.

SPECIFICATION forming part of Letters Patent No. 330,593, dated November 17, 1885.

Application filed August 10, 1885. Serial No. 174,017. (No model.)

To all whom it may concern:

Be it known that I, WILLIAM E. LAWRENCE, a citizen of the United States, and a resident of New York, in the county of New York and State of New York, have invented certain new and useful Improvements in Curry-Combs, of which the following is a specification.

My invention relates to that class of curry-combs provided with cleaning attachments; and it consists in the construction and arrangement of the attachment and comb, as fully set forth hereinafter, whereby I obtain increased rigidity and durability, and at the same time cheapen the manufacture.

15 In the drawings, Figure 1 is a plan view of a curry-comb embodying my invention. Fig. 2 is a rear end view showing the cleaning attachment locked in place. Fig. 3 is a front end view with the attachment swung away from the comb. Fig. 4 is a sectional view of the comb and attachment. Fig. 5 is a perspective view of the cleaning attachment, and Figs. 6 and 7 are modifications of the attachment.

The body A of the comb, the handle B, and 25 comb-bars a may be constructed and arranged in any suitable or usual manner, and with these parts is combined the comb-cleaning piece C. This piece consists of the scraping-bars b b and end plates, d d'. The bars b may 30 be separate plates or strips, as shown in Fig. 7, or they may be formed by making parallel slots x in a continuous plate, as shown in the other figures of the drawings. The end plates, d d', are preferably of cast metal, cast with 35 lugs e, adapted to extend through openings in the scraper-plates, and to be riveted down on and thereby secure the end and scraper plates together, or separate rivets may be used for the same purpose. The end plate d is provided with projections, perforated and turned 40 up to form ears c c, adapted to receive a cross-rod or projecting pins, i, extending from the body of the comb, and serving as pintles on which the cleaning-piece may be swung either 45 to the position shown in Fig. 4, with the bars b close to the comb-back, or outward, as shown in Fig. 3, to cause the bars b to scrape and clean the comb-bars. The end piece d' is provided with a projection, s, upon which 50 pressure may be applied to carry the cleaning-piece away from the comb-body.

To retain the cleaning-piece in place when in the position shown in Fig. 4, I use a spring, L, with a rounded terminal rib, u, which extends through a slot, y, in the back comb-bar, 55 and catches beneath the inner bar or plate b of the cleaning-piece and holds it in place until sufficient power is applied to force back the spring and let the bar b slip past the same.

Heretofore it has been common to secure retaining-springs to the handles, so that if the latter become loose or lost the spring was displaced and failed to secure the cleaning-piece in position. To prevent this, I secure the spring to the comb-body at some point—for 60 instance, to the brace or standard m, extending from the tang downward to the inner comb-bar. The plates d d' not only serve as means of connecting the bars b to each other, and of imparting rigidity to the cleaning-piece, but 65 they also serve, when the cleaning-piece is thrown in, to brace and strengthen the comb-bars, and as a means of connecting the bars to the comb-body.

I have shown the plates d d' as separate; but 75 they may be connected in one piece with side bars or strips.

To further strengthen the scraping or cleaning piece I may provide each plate d d' with fingers t, extending inward, and preferably riveted by rivets e' to the plates or bars.

Without limiting myself to the precise construction and arrangement of parts shown, I claim—

1. A curry-comb provided with a cleaning-piece, C, consisting of strips or plates b and end plates, d d', secured to said strips, substantially as set forth.

2. The combination, with the curry-comb having a cross-bar i, of a cleaning-piece consisting of strips b and end pieces, d d', the former carrying perforated ears c c, adapted to receive said pins, substantially as set forth.

3. The combination of the comb and hinged cleaning-piece consisting of the strips b and 95 terminal cross-plates d d', secured to said strips, one of the cross-plates having a projection, s, for the purpose set forth.

4. The combination, with the scraper-blades b, of end plates, d d', secured thereto and having inward-projecting fingers t, substantially as set forth.

5. The combination of the comb - body, hinged cleaning-piece C, and spring secured to the body and extending through one of the comb-bars to engage with the scraper, as set forth.

6. The comb provided with an inner bar having a slot, y, in combination with a hinged scraper - piece and with a spring secured to the body and provided with a lip or rib ex-

tending through the slot, substantially as set forth.

In testimony whereof I have signed my name to this specification in the presence of two subscribing witnesses.

WM. E. LAWRENCE.
